CLAIM

The ornamental design for a trolling motor housing, as shown and described.

DESCRIPTION

FIG. 1 is a right side and front perspective view of a trolling motor housing, showing my new design;

FIG. 2 is a top plan view thereof;

FIG. 3 is a left side elevational view thereof;

FIG. 4 is a front elevational view thereof;

FIG. 5 is a rear elevational view thereof;

FIG. 6 is a right side elevational view thereof; and

FIG. 7 is a bottom plan view thereof.

The broken lines shown in phantom in FIG. 1 are for illustrative purposes only and form no part of the claimed design.

FIG. 1

FIG. 5

FIG. 4

FIG. 6

FIG. 7
